UNITED STATES PATENT OFFICE.

STEPHEN S. KRAYER, OF ST. LOUIS, MISSOURI.

GAS-ENGINE.

1,096,544.

Specification of Letters Patent.

Patented May 12, 1914.

Application filed January 23, 1912. Serial No. 672,978.

To all whom it may concern:

Be it known that I, STEPHEN S. KRAYER, a citizen of the United States, residing at the city of St. Louis, State of Missouri, have 5 invented a new and useful Gas-Engine, of which the following is a specification.

This invention relates to gas engines, and consists in the novel design, arrangement and combination of parts hereinafter described, illustrated in the drawings and specifically pointed out in the appended claims.

One object of the invention is to provide a simple, durable and economical gas motor, 15 equipped with a single rotary valve element which controls the gas inlet and exhaust ports of a plurality of piston cylinders, thus obviating the well recognized disadvantages incident to the usual spring actuated valves, 20 cam shafts, rocker arms, et cetera, common in gas engines of usual construction.

Another object is to provide suitable and simple means for operating the above-mentioned valve element, so that it will operate 25 positively and in unison with the co-operating parts in performing the function attributed to it.

Other objects and advantages are to be attained by my present invention, which will 30 be apparent to those skilled in the art to which it appertains, without specific mention thereof.

In the drawings, in which like characters of reference indicate like parts throughout 35 the several views, Figure 1 is a horizontal sectional view of the engine, disclosing the pistons, the gas inlet passages, and the co-operating rotary valve element, the gear connections between the crank shafts, and between the driven shaft and the valve actuating 40 shaft, being shown in dotted lines; Fig. 2 is a vertical sectional view substantially on the line $a-a$ of Fig. 1 illustrating all the essential details of construction of my improved engine; Figs. 3 and 4 are detail horizontal sectional views, showing respectively, 45 the gas inlet passages, and the exhaust passages to and from the several cylinders, and the manner in which the cylinders are disposed 50 about the central chamber or valve case, wherein the rotary valve element is mounted; Fig. 5 is a detail perspective view of the valve element; Figs 6, 7, 8 and 9 are diagrammatic views, illustrating the position 55 of the pistons in the several cylinders, and the corresponding position of the rotary

valve element; and Fig. 10 is a detail vertical sectional view of the rotary valve element, showing the intake port of one cylinder, and the exhaust port of another adjacent cylinder, open.

In the embodiment of my invention illustrated in the drawings, I have shown the engine mounted in a vertical position, and in designating the various views I have referred to the horizontal and vertical sections of the engine merely for designating the views, and it will be understood, therefore, that the engine may be mounted in either position, and that I do not in any sense limit myself to any particular mounting of the engine, but that my improved engine will operate as effectively in one position as in another, and therefore, that it may be used in automobiles, for marine purposes 75 or as a stationary engine, in short for any purpose for which the ordinary gas motor may be used.

Referring to the drawings the engine casing 1, contains a plurality of piston cylinders A, B, C, and D, and a central tubular passage or chamber 2, constituting a valve case, and about which the several piston cylinders are arranged in a rectangular series 80 in the manner illustrated in Fig. 1. Between the chamber 2 and the piston cylinders are intercommunicating passages 3 and 4, arranged one above the other, and separated by a wall. The upper passage 3 constitutes 85 an inlet passage from the chamber 2 to the cylinders for the admission of gas from a remote source of gas supply, not shown, to said piston cylinders, and the lower passage 4 provides an exhaust passage or means of egress for the products of combustion resulting 90 from the explosion of gas in the cylinders, from said cylinders to atmosphere. A bushing 5 is seated in a threaded orifice in the upper part of the engine casing 1, adjacent to the upper end of the chamber or 95 passage 2, and constitutes a means for connecting a pipe or passage for the introduction of gas from the source of supply into the upper end of said chamber 2. An outlet pipe or passage 6 leads from the lower 100 end of the chamber or passage 2 through the wall of the crank shaft case to the atmosphere as clearly appears by reference to Fig. 2 of the drawings, through which the gases and other products of combustion accumulating 105 in the lower part of the chamber 2 may freely exhaust. The walls of the engine

casing surrounding the upper part of the cylinders and the valve case are double forming a water jacket 7, whereby overheating of these parts of the engine may be prevented.

5 To the lower part of the engine casing 1 is removably attached a crank case 8, in which the crank shafts 9 are incased, the ends thereof being journaled in suitable bearings formed in said case. Said crank shafts 9 are each provided with two crank arms 10, rigid with said shafts, and disposed on opposite sides thereof, and also disposed with respect to one another in such a manner that when the arm on one crank shaft is up, the arm on the other in the same transverse line will be down as illustrated in Fig. 2 of the drawings. A piston 11, of usual type, is operatively mounted in each of the cylinders, and each piston is connected to one of the arms 10 by a connecting rod 12. The crank shafts 9 are connected together by suitable gearing, comprising the meshing gear wheels 13 in such a manner that they coöperate, unifying the power in 20 one of the shafts, which may be extended from the engine casing forming a drive or power shaft as indicated at 14 in Fig. 1.

A projection 15 formed integral with the engine casing 1 extends downwardly therefrom and constitutes a bearing for the vertical shaft 16, which extends into the valve chamber 2. The shaft 16 is operatively connected by a suitable chain of gearing, to the driven shaft, which chain comprises a spur gear 17 rigid on the driven shaft, which meshes with a gear wheel 18 carried on the shaft 19; said shaft being journaled in the crank case 8. The shaft 19 also carries, rigid thereon, a beveled gear 20, which gear 35 meshes with a coöperating beveled gear 21 affixed to the lower end of the shaft 16. The ratio of the gears comprising the chain is such that the rotation of the driven shaft corresponds with the rotation of the shaft 40 16, that is to say, the rotation of the two shafts is simultaneous in action.

The valve element 22 is rigidly affixed to the upper end of said shaft 16, and is actuated thereby. The valve element 22, illustrated in detail in Figs. 5 and 10, comprises preferably a tubular body portion, whose exterior diameter with respect to the interior of the chamber 2 is such that it fits closely therein preventing the escape of gas 50 through the passage 2, and yet of sufficiently less diameter than the passage so that it may revolve freely, when the engine is in operation. The valve element 22 is divided into two compartments by the wall or partition 23. In the wall of the lower compartment is formed an orifice 24, and in the wall of the upper compartment an orifice 25, the openings being ninety degrees apart, so that when the upper opening, which constitutes the gas inlet, registers with the in-

take passage of one of the cylinders, the opening in the lower compartment will register with the exhaust passage of the adjacent cylinder, as will clearly appear by reference to Fig. 10 of the drawings.

By a reference to the diagrammatic views (Figs. 6, 7 8 and 9) the operation of the engine may be readily comprehended. Taking Fig. 6 for a basis of description, the intake port of cylinder A is shown in a position, with respect to the inlet port of the valve element, at which the two openings are about to register at which time gas from the upper part of the chamber 2 begins to pass into the cylinder A. The piston is up, and has just started on its downward stroke, which action draws the gas into the said cylinder. It may be assumed that there has been one complete rotation of the valve element 22, so that as shown in the view referred to, cylinder B has been charged, the charge compressed and exploded, which last operation leaves the piston down, and about to start an up stroke. The opening in the lower part of the valve element 22 is about to be brought into registration with the exhaust passage of cylinder B, and as the piston moves upwardly, all the products of combustion resulting from the explosion which has just taken place, will be forced out into the lower compartment of the valve element, thence through the passage 6 to the atmosphere. The gas in cylinder C has been compressed and is about to be exploded by the usual device for the purpose, and cylinder D has just received a charge of gas, and the piston is about to move upwardly to compress the gas. The same relative actions as just described occur in each of the cylinders in succession, the positions of the respective parts being illustrated in the remaining diagrammatic views Figs. 7, 8 and 9, which indicate the action for one complete revolution of the valve element 22. It will be readily understood, that each cylinder is charged, the charge compressed, exploded, and exhausted at each revolution of the valve.

I am aware that several modifications in the structure may be made, and that such changes, as for instance the increasing or diminishing the number of cylinders may be made without departing from the spirit and scope of the invention. I do not limit myself, therefore, to exact details, but

What I claim and desire to secure by Letters Patent is—

1. A gas engine comprising a rectangular series of piston cylinders, a central tubular passage between and parallel with said cylinders, a tubular valve mounted in said central passage, a partition in and dividing said valve into an upper compartment and a lower compartment, a gas inlet passage communicating with the upper end of said cen- 130

- tral passage, a single passage through the wall of said valve above said partition, a passage from said central passage to each of said cylinders with which the said passage 5 in the valve registers successively, an exhaust passage from each of said cylinders to said central passage below said partition, a single passage in said valve adapted to register successively with said exhaust passages 10 when said valve is rotated, a crank shaft case, a passage from said central passage through the wall of said crank shaft case, a crank shaft journaled in said crank shaft case, a shaft entrained with said crank shaft, 15 and extending into said central passage and being connected to the partition in said valve, substantially as specified.
2. In a gas engine, an integral unitary structure comprising a rectangular series of 20 piston cylinders, and a central combined inlet and exhaust passage integrally supported parallel with said cylinders, and a separate inlet and outlet passage between each of said cylinders and said central passage, in 25 combination with a crank shaft case, a crank shaft journaled in said case, pistons mounted in said cylinders and arranged to drive said crank shaft, a passage communicating with said central passage and extending through 30 the wall of said crank shaft case, a shaft journaled in the wall of said passage extending into said central passage, a valve attached to said shaft in said central passage and arranged to control the said inlet and 35 exhaust passages of said cylinders, and gearing entraining said shaft with said crank shaft, substantially as specified.
3. In an engine, a casting comprising a central tubular valve case, a rectangular series of piston cylinders in said casting integral with said valve case, inlet passages 40 arranged in the same plane from said valve case of said cylinder, respectively, exhaust passages arranged in the same plane from 45 said cylinders respectively, to said valve case, and a water-jacket surrounding the up-

per part of said piston cylinders and said valve case, in combination with a tubular valve revolvably mounted in said valve case, a partition in said valve dividing it into an upper and lower chamber, a passage in said valve above said partition arranged to register with said inlet passages successively when said valve is rotated, a passage in said valve below said partition arranged to register with said exhaust passages successively when said valve is rotated, a crank case, an exhaust passage leading from the lower end of said valve case through the wall of said crank case, a crank shaft journaled in said crank case, and a vertical shaft extending into the valve case and having affixed to its upper end the said tubular valve, and having gear connection at its lower end with said crank shaft, substantially as specified. 65

4. In a gas engine, the combination with a plurality of engine cylinders arranged about and parallel with a central passage, and separate inlet and outlet passages between each of said cylinders and said central passage, of a valve in said central passage provided with a partition therein, a passage in the wall of said valve on one side of said partition adapted to register with the inlet passages to said cylinders, a second passage 70 through the wall of said valve on the opposite side of said partition adapted to register with the exhaust passages leading from said cylinders, a supply passage entering one end of said central chamber, an exhaust passage leading from the opposite end of said central passage, and mechanical connections for operating said valve, substantially as specified. 75

In witness whereof, I have signed this 80 specification in the presence of two subscribing witnesses.
